UNITED STATES PATENT OFFICE.

ARTHUR J. COUGHTRY, OF QUINCY, MASSACHUSETTS.

AIR-PORT.

1,192,992.

Specification of Letters Patent. Patented Aug. 1, 1916.

Application filed November 15, 1913. Serial No. 801,302.

To all whom it may concern:

Be it known that I, ARTHUR J. COUGHTRY, a citizen of the United States, and a resident of Quincy, in the county of Norfolk and State of Massachusetts, have invented a certain new and useful Air-Port, of which the following is a specification.

This invention has for its object the production of a ship air port or port hole, which is particularly simple in construction and highly efficient and durable in use, one of the principal objects being constructions whereby the light frame can be clamped on all sides equally against the packing ring or gasket inserted between the light frame and the sill; and the invention consists in the combinations and constructions hereinafter set forth and claimed.

In describing this invention, reference is had to the accompanying drawings in which like characters designate corresponding parts in all the views.

Figure 1 is an elevation, partly broken away, of a preferable embodiment of this air port. Fig. 2 is a sectional view on line A—A, Fig. 1. Figs. 3 and 4 are enlarged sectional views on lines B—B and C—C, Fig. 1.

This air port comprises, generally, a sill, a light frame hinged to the sill, and means for clamping the frame along its edge against the yielding gasket arranged in a groove in the sill.

1 is the sill arranged to be secured to the side or hull 2 of the ship, the sill having a ring or annular flange 3 adapted to fit a circular hole in the hull.

4 is the annular light frame suitably constructed to hold the pane of glass 5, and 6 is the gasket in a suitable groove in the sill 1 in position to be engaged by the inner circular edge 7 of the frame 4. The sill 1 is also formed with hinge leaves 8 and the light frame is also formed with hinge leaves 9 which are pivoted or hinged to the leaves 8 by hinge pins 10. These hinge pins 10 have axially alined spindles upon which the hinge leaves 9 are mounted, and outwardly extending inclined studs 11 movable in converging bearings 12 in the hinge leaves 8, said bearings converging inwardly toward the sill. The hinge pins are moved axially in order to move the studs 11 along their inclined bearings 12 and thus lower, that is, move the axially alined spindles toward the sill 1 in order that a portion of the edge 7

may be caused to fit more tightly the gasket 6.

The hinge pins 10 are operated by a member, common to both of said pins, here shown as a cam lever 13 pivoted at 14 to a post 15 rising from the sill 1 midway between the hinge leaves 8, the cam lever having opposite cams 16 extending eccentrically around the axis 14 and having a sliding engagement with the alined portions of the hinge pins 10.

Other means are provided for clamping the light frame toward and from the sill 1, said means acting on the portion of the frame farthest removed from the hinge and on opposite sides of a line passing centrally of the frame at a right angle to the axis thereof. Said means consists of members in the form of bolts 17 slidable in guides 18 on the sill 1 and having means coacting with the frame 1, the guides 18 being so arranged that the bolts 17 converge toward each other, an an operating member common to both bolts and connected thereto so that it acts equally and simultaneously on both bolts.

As here shown, the bolts 17 are provided with hook shape means 19 which enter eyes 20 on the light frame, the bills of the hooks 19 being usually inclined and entering inclined openings in the eyes so that as said bills move into the eyes, the free edge of the light frame is clamped toward the sill 1 to impress the edge 7 into the gasket 6. The bills of the hooks 19 act as wedges and either the eyes 20 or the bills of the hooks 19 or both may be inclined to effect the wedging action.

21 is the operating member common to both bolts 17, said operating member being disconnected from the sill and having an elliptical cam ring 21^a which extends through transverse openings 22 in the converging ends of the bolts and which fulcrum on the walls of said openings, so that the operating member 21 moves about a shifting axis located between its fulcrum points. Hence none of the force applied to the lever is transmitted to the bolts 17 through the sill 1 and the entire force of the member 20 is applied equally to the bolts 17. The member 21 includes a handle 24 pivoted at 25 thereto on a pivot extending parallel to the face of the sill or to the direction of movement of the member 21, the handle having a tooth 26 on its lower side coacting with a rack 27 on an exten-

sion 28 of the sill, the pivotal movement of the handle being for the purpose of disengaging the tooth 26 from the rack 27. The air port is arranged so that the handle 24 is normally in vertical position and falls by gravity into engagement with the rack 27. The light frame is held open in any suitable manner.

Owing to the arrangement of the clamping bolts 17 and their operating member, the clamping action is effected equally and simultaneously on the frame in one operation of the lever 20, thus insuring equal pressure on the gasket which is usually rubber, and avoiding bending of the frame as in constructions now in use. Owing to the construction of the hinge, vibration or rattling of the light is prevented when the air port is open as the hinge pins are never loose in their bearings, and the hinge is readily adjustable to the wear of the gasket.

Although I have shown and described my invention as applied to air ports, obviously it may be applied to other devices and windows and for the sake of brevity, I have used the term air port and other terms throughout the specification and claims.

What I claim is:—

1. An air port comprising a sill, a light frame hinged to the sill, and means for clamping the light frame toward the sill comprising a plurality of clamping elements movable relatively to each other, and an operating member common to the clamping elements to operate the same simultaneously, substantially as and for the purpose described.

2. An air port comprising a sill, a light frame hinged to the sill, and means for clamping the light frame toward the sill comprising a pair of clamping elements, and an operating member common to both clamping elements to operate the same simultaneously, said operating element being movable about a shifting axis and being disconnected from the sill, substantially as and for the purpose specified.

3. An air port comprising a sill, a light frame hinged to the sill, and means for clamping the frame toward the sill including members carried by the sill and coacting with the frame, said members comprising sliding bolts converging toward each other, and an operating member common to both the sliding bolts and coacting with the contiguous ends of the same, substantially as and for the purpose set forth.

4. An air port comprising a sill, a light frame hinged to the sill, and means for clamping the frame toward the sill including members carried by the sill and coacting with the frame, said members comprising sliding bolts converging toward each other, and an operating member common to both the sliding bolts and including a

double cam coacting with the converging ends of the bolts and slidably engaging the same, substantially as and for the purpose described.

5. An air port comprising a sill and a light frame hinged to the sill, and means for clamping the frame toward the sill including members comprising sliding bolts carried by the sill and having means coacting with the frame, the bolts converging toward each other, and a clamping lever having sliding connections with the converging ends of both bolts and fulcruming at the points of its sliding engagement with the bolts and movable about a shifting axis located between its fulcrum points, substantially as and for the purpose specified.

6. An air port comprising a sill, a light frame hinged to the sill, and means for clamping the frame toward the sill including movable members, and an operating lever having an elliptical cam coacting with said members and slidably engaging the same and fulcruming thereon whereby the lever moves about a slightly shiftable axis located between the fulcrum points thereof, substantially as and for the purpose set forth.

7. An air port comprising a sill, a light frame hinged to the sill, and means for clamping the frame toward the sill including members comprising sliding bolts carried by the sill and having wedging means coacting with the frame, and means for operating the bolts, substantially as and for the purpose described.

8. An air port comprising a sill, a light frame hinged to the sill, and means for clamping the frame toward the sill including members comprising sliding bolts carried by the sill and having means coacting with the frame, the bolts converging and being formed with transverse openings in their contiguous ends, and an operating lever including an elliptical cam ring extending through said openings and slidable in the same and fulcruming on the walls thereof, substantially as and for the purpose specified.

9. An air port comprising a sill, a light frame hinged to the sill, the sill being formed with guides and the frame being formed with eyes, clamping members comprising bolts slidable in the guides and having wedging means for entering the eyes, said guides being arranged on the sill so that the bolts converge toward each other, the bolts being formed with transverse openings at their converging ends, and an operating lever including an elliptical cam ring extending through the openings and slidable in the same and fulcruming on the walls thereof during the operation of the operating member, substantially as and for the purpose set forth.

10. An air port comprising a sill, a light frame hinged to the sill, and means for clamping the light frame toward the sill including clamping means, an operating means for the clamping means, and a stationary rack with which the operating member contacts to hold the said member in its adjusted position, substantially as and for the purpose described.
11. An air port comprising a sill, a light frame hinged to the sill, and means for clamping the light frame toward the sill including clamping means, an operating means for the clamping means, including a body and a handle pivoted to the body, and a stationary rack, the handle being movable on its pivot into and out of engagement with the rack, substantially as and for the purpose specified.
12. An air port comprising a sill, a light frame hinged to the sill, and means for clamping the light frame toward the sill including clamping means, an operating means for the clamping means, including a body and a handle movable relatively to the body, and a stationary rack, the handle being movable into and out of engagement with the rack, substantially as and for the purpose set forth.
13. An air port comprising a sill having a rack thereon, a light frame hinged to the sill, and means for clamping the light frame toward the sill, means for clamping the light frame toward the sill including clamping mechanism, and an operating member movable about an axis and including a pivoted handle movable at an angle to the axis of said member into and out of engagement with said rack, to hold said member in its adjusted position, substantially as and for the purpose described.
14. An air port comprising a sill, a light frame hinged to the sill, and means for clamping the frame toward the sill including a sliding bolt and an operating member connected to the bolt, and a stationary rack coacting with the operating member, substantially as and for the purpose specified.
15. An air port comprising a sill, a light frame hinged to the sill, means for clamping the frame toward the sill comprising sliding bolts carried by the sill and having means coacting with the frame, the bolts converging toward each other, and a clamping member having sliding connection with the converging ends of both bolts, the clamping member being movable about an axis, and including a shiftable handle, a fixed rack coacting with the operating handle to hold said member in its adjusted position, the handle being shiftable into and out of engagement with the rack substantially as and for the purpose set forth.
16. An air port comprising a sill, a light frame hinged to the sill, hinge pins connecting the light frame and the sill, and means for moving the hinge pins toward and from the sill to tighten the light frame on the sill, said means comprising an operating lever common to both hinge pins, substantially as and for the purpose specified.
17. An air port comprising a sill, a light frame hinged to the sill, hinge pins connecting the sill and the frame, the sill being formed with converging bearings for the hinge pins and the hinge pins having alined spindles on which the frame is mounted and studs inclined relatively to the spindles and arranged in said incline bearings, and an operating member connected to the hinge pins to shift the same axially and thereby move their inclined studs in the inclined bearings of the sill, substantially as and for the purpose set forth.
18. An air port comprising a sill, a light frame hinged to the sill, hinge pins connecting the light frame and the sill, and means for moving the hinge pins toward and from the sill to tighten the light frame on the sill, a pair of clamping members carried by the sill and coacting with the light frame near the portion thereof farthest removed from the hinge and on opposite sides of a line extending centrally of the light frame and at a right angle to the axis of the frame, and an operating element common to both of said clamping members and including means whereby both clamping members are operated equally and simultaneously, substantially as and for the purpose described.

In testimony whereof, I have hereunto signed my name in the presence of two attesting witnesses, at Syracuse, in the county of Onondaga, in the State of New York, this 16th day of October, 1913.

ARTHUR J. COUGHTRY.
